CARBURIZING BOX

Angus M. Miller, Pleasant Ridge, Mich.

Application September 11, 1936, Serial No. 100,330

7 Claims. (Cl. 263—49)

My invention relates to carburizing boxes and relates more particularly to carburizing boxes of a type having walls in the form of plates or sheets of heat resisting material.

5 In the use of carburizing boxes, metal articles to be carburized are placed in the boxes, together with any suitable carburizing agent such as bone dust. The boxes are commonly introduced into a heat treating furnace, with suitable covers, in 10 trays, and when so introduced are subjected to the heat of burning gases projected into the furnace and which are usually directed against the sides and ends of the box, to cause heat to permeate the box, the contained articles, and carburizing agent, until the articles are heated to a 15 desired pre-determined temperature, whereupon the metal articles absorb carbon from the carburizing agent.

The effect of the temperature which may reach 20 from 1600° to 1800° Fahrenheit is to add to the carbon content of the surface portions of the iron or steel articles. After the carburizing operation, the boxes are then withdrawn from the furnace and cooled, and the accrued heat imposed 25 upon the articles becomes gradually dissipated. Consequently the boxes are subjected to extreme variations in temperature and in former constructions, due to the expansion and contraction of the walls of such boxes, and more particularly 30 the side walls, these walls commonly become permanently warped, fractured or otherwise damaged.

Also in prior constructions there has been 35 difficulty incurred, in that some of the metal articles placed in the box to be carburized become heated to carburizing temperature more rapidly than other articles differently disposed in the box, and the reverse condition, that some of the articles are cooled more rapidly than other differ- 40 ently disposed articles, also commonly obtains, with the result that the articles are not uniformly carburized.

It is therefore an object of my invention to provide an improved carburizing box whereby all of 45 the articles placed therein, and subjected to the carburizing temperatures, are more uniformly subjected, and for more uniform periods, to corresponding variations in temperature, both during the heating and cooling periods.

50 Another object of my invention is to provide an improved carburizing box, which will withstand the temperature conditions incidental to the use of such a box, under the conditions of practice with minimum deterioration.

55 Another object of my invention is to provide

a box which will not only efficiently withstand the temperature conditions of practice, but at the same time, will withstand the hard mechanical usage imposed upon such a box in practice.

Another object of my invention is to provide a 5 carburizing box having lateral walls preferably continuous throughout their length, and which are so associated with the corners, as to provide what I term a full-floating construction wherein said walls are not rigidly secured to the corners. 10

Another object of my invention is to provide a carburizing box wherein the preceding objects may be achieved, and at the same time wherein the advantageous results arising out of a spaced 15 double wall construction may also be achieved.

Another object of my invention is to provide an 20 improved carburizing box having sheet metal walls so formed and disposed relative to the corners, that thermal expansion and contraction and mechanical usage will not unduly derange 25 the form of the walls, and will not cause the walls to deteriorate, and will not effect breakage due to crystallization adjacent the corners which hold 30 said walls in position.

Other objects of the invention will be apparent 25 to those skilled in the art to which my invention appertains, from reference to the accompanying drawing, and from the descriptive specification referring to said drawing, and which disclose a preferred embodiment of my invention.

Referring to the drawing:

Fig. 1 is a top plan view of a carburizing box which is an embodiment of my invention;

Fig. 2 is a side elevational view of said box;

Fig. 3 is approximately a perspective view of 35 the corner construction illustrating the junction of corner elements with the continuous side wall plates, a portion of the corner elements being illustrated in section;

Figs. 4 and 5 are respectively horizontal sec- 40 tional and vertical sectional views of a corner element, and the adjacent associated portions of the double side wall plates;

Fig. 6 is a plan view of a carburizing box cover;

Fig. 7 is a side elevational view thereof;

Fig. 8 is a vertical sectional view taken on the line 8—8 of Fig. 6.

Referring now to the carburizing box illustrated in Figs. 1, 2, 3, 4 and 5, the embodiment 50 of the carburizing box of my invention illustrated in said figures, is provided with a single pair of side wall sheets or plates 3 and 4, which are bent into generally rectangular form with rounded corner portions 3' and 4' in which form they 55

are held by being fitted within oppositely extending arcuate slots 5 of the corner elements 2.

The lateral wall portions 3 and 4 extend divergently outwardly from preferably within the slots 5, and are most greatly relatively spaced intermediate the corners 2, and the spacing at said intermediate portion is maintained by a spacer element 6, which extends longitudinally of the box axis and intermediate the plates 3 and 4, being welded as by a laterally extending flange 7 preferably to the inner surface of the outer plate 4.

The plates 3 and 4 being each preferably in one piece, and each have their ends welded together as indicated at 8 for the inner wall plate, and at 9 for the outer wall plate.

The corner elements each comprise a pair of like relatively reversed parts 10 and 11 having oppositely disposed hook shaped flanges 12.

20 The corner element parts 10 and 11 are welded together at their corresponding and abutting ends as shown at 13, preferably medially of the ends of the box. Each of said plates is provided with an arcuate intermediate portion 2' and an inwardly extending end flange 12 with a reversely turned flange portion 12'. Said flange 12 and flange portion 12' are arcuately formed corresponding to the curved portion 2' of the corner element, and there is thereby provided an arcuate slot 5 into which the inner and outer plates 3 and 4 may be loosely projected. The slot 5 at its ends 13 and 14 has divergently formed lateral walls to prevent localization of bending fatigue stresses at the point of emergence of said plates 3 and 4 from said slot 5.

35 The plates 3 and 4 are only loosely fitted in the corner elements 2 whereby the "full-floating" characteristic of the sheet metal walls is provided. The spacers 6 prevent more than a pre-determined relatively approaching movement of the walls 3 and 4, but do not limit the relatively outward bowing of said walls under the influence of high temperatures.

40 In the use of the box of my invention, however, assuming that the box, perhaps with other boxes, is placed in a suitable tray and provided with any suitable top closure, and introduced into the carburizing furnace, the side walls of the boxes are subjected to the heat of burning gases or other source of heat provided in the furnace for a pre-determined length of time, and at the same time heat is communicated through the bottom tray and top cover to the carburizing material and articles to be carburized in the box.

45 In single walled boxes of the prior art, it has been found that heat commonly penetrates the side walls and is communicated to the articles disposed most nearly adjacent to said side walls more rapidly than to articles placed nearer the center of the box, and also that such more nearly adjacent articles are cooled more rapidly than the more centrally disposed articles. This results in a difference in carburizing results imposed upon the said differently disposed articles 55 in the box.

50 Another difficulty which has been prevalent with single walled boxes is that heat is transmitted through the lateral walls more rapidly than from the tops and bottom and with a result-70 ant difference in carburizing results with respect to some of the lateral surfaces of articles positioned relative to other surfaces which may be faced towards the top or bottom.

75 The carburizing agent being a quite efficient form of heat insulation material, and being so

placed as to surround the articles in the box, adds to the difficulties such as those above mentioned, which have been previously prevalent.

In my improved double wall construction, the air space between the outer wall and inner wall 5 elements, retards the flow of heat communicated to the outer wall element, to the articles placed within the box.

In my improved box having the relative dimensions as illustrated in the drawing, it is 10 found that heat transmitted to the articles disposed over the major portion of the interior of the box, from the top and bottom of tray and cover elements, arrives at the articles within the box, at about the same time as the heat transmitted through the double walls, and communicated laterally to such articles. 15

Conversely after the carburizing operation, and upon cooling, heat is dissipated in all directions from the articles at approximately the 20 same rate, or in any event, at a more uniform rate in all directions than has been previously attained in boxes of this general character.

Now referring to Figs. 6, 7 and 8. I have illustrated therein a form of top or bottom cover element, which I prefer to use with the box of my invention, although obviously, said box is not limited to any particular form of cover or tray, and may be employed in connection with any well known form of cover or tray. 25

The cover of said figures which may also be used with other forms of boxes comprises a substantially rectangular plate 15, loosely held between parallel flanges 16 and 17, which extend inwardly from a relatively short substantially rectangular tubular frame 18. 30

The frame 18 with the inwardly extending flanges 16 and 17 is preferably made of two separate castings 19 and 20, welded together at preferably diametrically opposite points 21 and 22, the line of weld extending preferably parallel to the axis of the frame.

Between the portion of the plate 15 which extends between the flanges 16 and 17, and the frame element 18 excluding said flanges, sufficient clearance is provided, so that the plate relative to said frame is relatively floating in the slot provided by said flange, in both lateral and vertical directions within predetermined limits. 45

In Fig. 8 the position of a carburizing box 20 50 with respect to which the cover of Fig. 8 may be employed is shown.

Ordinarily the box of my invention is used in connection with trays of the ordinary types on which the boxes are placed, but under special 55 conditions, a cover element such as illustrated in the foregoing figures may be employed as a tray, and when so employed the plate 15 should preferably be made heavier.

Having thus described my invention in a preferred embodiment, and with a preferred form of top and bottom, I am aware that numerous and extensive departures may be made from the invention herein illustrated and described, but without departing from the spirit of my invention, I claim:

1. In a carburizing box, a pair of one-piece relatively telescoped spaced sheet metal wall elements each bent to substantially closed rectangular form, said box comprising said sheet metal elements and corner elements, said corner elements loosely embracing the top and bottom edge portions of suitably bended corner portions of said wall elements. 70

2. In a carburizing box, a pair of one-piece relatively telescoped sheet metal wall elements each bent to substantially closed rectangular form, said box comprising said sheet metal elements and corner elements, said corner elements loosely embracing the top and bottom edge portions of suitably bended corner portions of said wall elements, said wall elements being of substantially bowed form intermediate each pair of adjacent corner elements, whereby they are separated from each other providing an air space between said elements.
3. In a carburizing box, a pair of one-piece relatively telescoped sheet metal wall elements each bent to substantially closed rectangular form, said box comprising said sheet metal elements and corner elements, said corner elements loosely embracing the top and bottom edge portions of suitably bended corner portions of said wall elements, said wall elements being of substantially bowed form intermediate each pair of adjacent corner elements, whereby they are separated from each other providing an air space between said elements, and spacer means interposed between said inner and outer wall elements intermediate said corners, to ensure a predetermined separation between said wall elements adjacent said spacer means.
4. A carburizing box comprising a pair of substantially continuous one-piece substantially tubular sheet metal spaced walls, each wall bent to generally rectangular form, and corner elements, said corner elements having flanged ends and provided with relatively confronting slots on the flange of each end, said wall elements being received within both of the confronting slots of each corner element.
5. A carburizing box comprising a pair of substantially continuous one-piece substantially tubular spaced sheet metal wall elements, each wall element bent to generally rectangular form, and corner elements, said corner elements having flanged ends and provided with relatively confronting slots on the flange of each end, said wall elements being received within both of the confronting slots of each corner element.
6. In a carburizing box, a pair of one-piece relatively telescoped sheet metal wall elements each bent to substantially tubular rectangular form and with their abutting edges secured together, a corner element secured to said wall elements at the corners thereof, said corner elements embracing the top and bottom edges of the corner portions of said wall elements by slots of said corner elements, the size and form of said slots being such as to ensure a loose clamping fit between said wall elements and said corner elements, said wall elements extending divergently from each of said corner elements and relatively spaced over at least the major portion of their lengths between corner portions.
7. In a carburizing box, a pair of one-piece relatively telescoped sheet metal wall elements each bent to substantially tubular rectangular form and with their abutting edges secured together, a corner element secured to said wall elements at the corners thereof, said corner elements embracing the top and bottom edges of the corner portions of said wall elements by slots of said corner elements, the size and form of said slots being such as to ensure a loose clamping fit between said wall elements and said corner elements, said wall elements extending divergently from each of said corner elements and relatively spaced over at least the major portion of their lengths between corner portions, and spacer means to ensure at least a predetermined spacing of said wall elements intermediate said corner elements.
